UNITED STATES PATENT OFFICE.

WILLIAM HARSEN, OF NEW YORK, N. Y., ASSIGNOR TO HIMSELF AND FRANCIS N. BANGS,
OF SAME PLACE.

ROCK-DRILL.

Specification forming part of Letters Patent No. 31,430, dated February 12, 1861; Reissued
August 11, 1874, No. 6,009.

To all whom it may concern:

Be it known that I, WILLIAM HARSEN, of the city, county, and State of New York, have invented a new and useful Portable 5 Pneumatic Rock-Drill; and I do hereby declare the following to be a correct description of the same, reference being had to the accompanying drawings, in which—

Figure 1. is a perspective view of the drill complete; Fig. 2. is a side elevation of the same with the shells removed; Fig. 3. is a longitudinal section through the tappet bar; Fig. 4 is a bottom end view; Fig. 5, is a top end view; Fig. 6. is a longitudinal section 15 through lines W, W, of Figs. 7 and 8; Fig. 7. is a transverse section through lines Y, Y, of Figs. 2. and 6; Fig. 8. is a transverse section through lines Z, Z, of Figs. 2 and 6; Fig. 9 is an end view of Fig. 6. in direction 20 of arrow marked 13; Fig. 10. is an end view of Fig. 6. in the direction of the arrow marked 14; Fig. 11. is a transverse section of the upper shell, with the upper end of the machine shown therein; Fig. 12 is a longitudinal section of the upper shell in the direction 25 of the arrow 15.

The same part is marked by the same letter of reference wherever it occurs.

The nature of my invention consists in 30 the construction of a rock drill, to be operated by steam or compressed air, and which is, at the same time, portable, capable of operation in any direction, and exposed to wear only in parts which can be readily and 35 cheaply renewed, all as hereinafter more particularly set forth.

To enable others to make and use my improved drill, I will proceed to describe its construction and operation, with reference 40 to the drawings, in which A marks the cylinder, or main body of the machine; B, the cylinder heads; C, the piston attached to D, the hollow piston rod.

Attached to the ends of the piston rod by 45 collars, are heads E, which allow the rod to rotate in them, but have no end play.

F is the tappet bar secured at its ends to the heads E.

G, G', mark tubes fixed to heads E, and 50 playing through stuffing boxes, into the cylinder, in lines parallel to the piston rod.

H is a bottom piece firmly secured to the piston rod, and forming with piece n', a collar.

I is a top piece secured to the piston rod,

and forming a collar with the piece n; J, the ratchet wheel for revolving the drill; K, band revolving around wheel J; L, a projection from band K, having in it a spring pawl r; M, lower gibs for nipping the tool; 60 N, upper gibs for the same purpose; O, ring for operating gibs M; P, ring for operating gibs N.

Q marks the steam or air chest; R a cap, covering the valve rod connection; S, shells 65 covering and protecting from injury, the ends of the machine.

T is the bit or drilling tool; U a coupling connecting the valve chest with a tube or pipe from the steam boiler, or air pump, 70 which is the source of power.

a marks the bottom inlet port; b, the exhaust port; c, upper inlet port; d, valves; e, valve rod; f, box in which tappet bar F, plays; g, a projection forming a fulcrum 75 for a starting lever; h, the upper tappet; i, the lower tappet; j the feather on which bar F slides, and by which it is steadied; k, movable caps; l, stuffing box glands; m holes in the sides of tubes G; n, n', collar 80 pieces fixed to piston rod; o, leather buffer on piece n; p, leather packing, on head of rings O, and P; q, piston packing; r, spring pawl working into ratchet wheel J; s, s', bases of shells; t, t' caps of shells; 85 u, u', horns of caps t, t'; v, orifice through which the bit T, passes and plays; w, channel in which the pieces w', w² form a spiral way for guiding the motion of projection L; w, w', walls of shells S; y and z y', z', and 90 w³ channels on the interior of shells S, to accommodate projecting parts of the machine; a', the way from inlet port a, into cylinder; b', the outlet for exhaust; c' the way from inlet port c, into cylinder; d', 95 rings for holding and securing the machine; e', light wire springs to hold the gibs out; i' stuffing box gland for valve rod.

The construction of the cylinder, piston, valves, steam chest, &c., is essentially like 100 that of the simplest form of steam engine. The cylinder A, of the usual form, is provided with substantial heads B, and stuffing boxes l. The piston C, has the ordinary packing, shown in black at q, Figs. 3, 6, 105 7 and 8, and receives, and is firmly attached to the piston rod D. It is in this rod, and the parts attached to, and surrounding it, that the chief novel peculiarities of the machine are to be found. The piston rod D, 110

is hollow throughout its entire length, and is attached at its middle, to the piston C, and has a reciprocating motion with it, in the usual way. At either end of the rod D, 5 are attached collars I, n, and H, n', which snugly grasp the annular heads E, and are capable of revolving in them, but have no end play. To these heads, the tappet bar F, is strongly framed, (see Figs. 2 and 3.) 10 Each of the heads E, has in it a deep annular groove, for the reception of the rings O, and P, respectively; and, opposite to and communicating with those grooves, are the orifices for the reception of the tubes G, 15 on the lower end, and the tubes G' on the upper. These tubes G, G', pass through stuffing boxes into the cylinder A, and terminate near the piston C, as clearly shown in Figs. 3 and 6. Being part of the same 20 system with the piston rod D, they move with it. The tubes G, are closed at their inner ends, and open at the ends which are inserted into the head E. They have, near their inner ends, the small lateral openings 25 m. The tubes G', are open at both ends. The rings O, and P, are beveled on the inner side of their outer ends, to correspond with the angle of their respective gibbs, M and N. Their inner faces are provided with 30 packing, shown in black at p, Fig. 3, to render air tight their connection with the tubes G, G'. The bottom piece H, and collar I, are made with slanting channels upon 35 which the gibbs, M and N, bear and slide, as shown in Fig. 3.

The tappet bar F, has a groove in its under side, extending its whole length, and traverses upon a feather j, made to fit this groove. Its sides are armed with the tappets h, and i, which are placed at the proper 40 points to operate the valves at the right time. The box f, has a mortise through it, in which the bar F, plays and causes the tappets h, and i, alternately to strike the sides of the 45 mortise, and thus work the valve rod e. A small transverse mortise is also made in the top of slide box f, (see Fig. 2.) to receive the end of a starting lever, which may be inserted through fulcrum piece g, Fig. 1. 50 The valve rod e is secured to box f, and passes through stuffing box i', into the valve box, and is attached at its inner end to the valve d, see Figs. 7 and 8.

The ratchet wheel J, Figs. 3 and 5, forms 55 part of collar I, so that, when it turns, that collar, and the piston rod D, attached to it, will turn at the same time. Outside of collar I, and wheel J, is placed annular band K, with its projection L. In the latter, is 60 a spring pawl r. By this construction and arrangement, the band K, plays freely around the ratchet wheel J, in one direction, but carries the wheel, collar, and piston-rod around with it, in the other direction, see 65 Figs. 2, 3 and 5. The projection L, is made

to fit a spiral groove in one of the channels of the upper shell, as shown in Fig. 12, and, by sliding up and down in that groove, operates the pawl and ratchet.

The air or steam chest Q, is provided with 70 a nozzle or coupling U, by which a connection may be made with a tube or pipe, leading from a steam boiler, or air pump, or other source of power.

The working ends of the machine are protected from injury by being incased in shells S, S, of proper size and shape to contain them. Rings d', Fig. 1., are attached to the outside of the shells, for purposes of fastening or handling. One of the ribs or channels of the upper shell is fitted with two wedge shaped pieces w', and w², for the purpose of making a slanting or spiral groove for the projection L to work in, as herein-before described, and shown in Fig. 12. 75 80 85

Operation: The operation of the machine is as follows: The drill bit, or tool, T, having been inserted in the hollow of the piston-rod D, motion is imparted to the piston by means of steam, or compressed air, 90 which is let in through the nozzle U, into the steam or air chest Q. The air, thus admitted, passes through inlet port a, and way a', into the cylinder below the piston, and forces it upward. As soon as it has moved 95 upward a short distance, the holes m, in the sides of the tubes G, are brought into the interior of the cylinder A, when the air, or steam, at once rushes through them into the tubes, and, exerting its pressure against the 100 inner face of the ring O, drives that ring outward against the inclined sides of the gibbs M, pressing the gibbs inward toward the center of the piston-rod, and causing them to nip the bit tightly, and hold it until released by a reversal of the position of the valves. Just before the piston has reached 105 the end of its upward stroke, tappet i, changes the valves, and the lead gives an air cushion for the piston, and thereby prevents shock. By the change of the valves just mentioned, the steam or air is directed into port e, and through way e', to the upper side of the piston, while the steam, or air, in the lower side, is exhausted in the 110 usual way, through the exhaust port b.

While the piston is being driven down, the air, or steam, enters tubes G', and, pressing upon ring P, drives its beveled edge against gibbs N, which are thus forced in against the 115 tool, and firmly grasp it, and carry it down to its stroke against the rock. The piston is cushioned, at the end of its downward stroke, by the lead, in the same manner as in its upward stroke. 120 125

During the upward stroke of the piston, the piston rod, with the tool held within it, is turned part of a revolution, by the ratchet wheel, which is operated by the pawl attached to projection L. During the down- 130

ward stroke, the pawl slips over the teeth of the wheel, and does not turn the tool.

It will be observed that, when the bit strikes the rock to be drilled, its rebound, instead of producing a destructive jar, or shock, to the machine, merely causes the tool itself to slip through the nipping gibs, which are thus the only parts exposed to any considerable wear. As they can be cheaply 10 and readily replaced, as often as may be required, one of the chief objections to machines of this class—their rapid destruction—is completely obviated. It will be further observed that, if the lower gibs were 15 made to nip the tool at the same time that it struck the rock, it would grasp it so near its lower end as to impair the efficiency of the succeeding blow. To prevent this, the gibs M, are not operated until the piston has 20 made so much of its upward stroke as to bring the holes *m*, in the sides of tubes G, within the cylinder. Thus they are made to take hold of the tool at a point sufficiently high to insure a good blow at the following 25 downward stroke.

It is obvious that by substituting a hammer, or pounding tool, for the drill bit, the machine may be used as a pounding or stamping engine for the reduction of ores 30 &c. I contemplate using it for such purposes.

Having thus fully described my invention, what I claim, and desire to secure by Letters Patent, is—

1. The gibs M, N, constructed and operating substantially as, and for the purpose specified.

2. The combination of the hollow piston rod D, the gibs M, N, and the rings O, P, constructed and arranged for conjoint operation substantially as described.

3. The combination of the rings O, P, with the tubes G, G', and the cylinder A, in the manner and for the purpose substantially as described.

4. The combination of the tappet bar F, slotted box *f*, and valve rod *e*, constructed and operating as, and for the purpose described.

5. Operating a drill tool or pounder by 50 the direct application of steam, or compressed air, to the tool holder, substantially in the manner set forth.

6. The holes *m*, in the tubes G, for the purpose specified.

The above specification, signed and witnessed this first day of November, A. D. 1860.

WILLIAM HARSEN.
